CHARLES N. TEETOR, OF HAGERSTOWN, INDIANA.

MECHANISM FOR SLOTTING PISTON-RING CASTINGS.

Application filed October 25, 1926. Serial No. 144,022.

My invention relates to a mechanism for slotting piston ring castings which are initially formed in elliptical shape in order that they may assume circular shape after 5 being slotted and put into use.

Hitherto, in slotting such a ring, a ring section was removed leaving ring end portions having opposed parallel end faces while the ring is uncontracted. A ring in 10 this condition, when contracted to bring the opposed end faces thereof together, will bring these end faces out of parallelism with the result that a V-shaped gap, diverging toward the interior of the ring, is 15 formed by the adjacent end faces of the ring which would impair the functioning of the ring. By means of the mechanism and method of my invention, the ring is further shaped at its slot whereby the opposed 20 faces of the ring ends are brought into parallelism when the ring is contracted in being put into service.

In carrying out my invention, the ring is pressed inwardly at the slot formed there- 25 through in a flatter side thereof to cause the opposed faces of the ring ends to diverge toward the interior of the ring whereafter the ring is shaped at the slot, while the ring ends are thus positioned, to bring the 30 opposed faces of the ring ends substantially into parallelism. When the ring is released from its holding means, the opposed end faces thereof will converge toward the interior of the ring, instead of diverge, and 35 just sufficiently to cause these faces to become parallel when fully or nearly meeting when the ring is located within an operating piston and is held contracted by the cylinder surrounding the piston. In accordance 40 with the preferred method of my invention, both of the ring ends are thus pressed inwardly and are trimmed to shape the ring at its slot in the manner and with the results 45 previously set forth.

The mechanism of my invention includes a holder for the ring and slot forming saw, the holder and saw being relatively adjustable to enable the saw to form a slot, having substantially parallel opposite faces, through 50 a flatter side of the ring, and means for pressing the ring inwardly at the slot to cause the opposed faces of the ring ends to diverge toward the interior of the ring, the saw being again operative to shape the ring at 55 the slot while the ring ends are thus positioned to bring the opposed faces of the

ring ends substantially then into parallelism. In the preferred embodiment of the invention, both of the ring ends are pressed inwardly and the saw is operative upon these 60 ring ends with the results and for the purpose stated.

I will explain my invention more fully by reference to the accompanying drawings in which Fig. 1 is a view, in elevation, 65 of the preferred mechanism of my invention, parts being broken away and a supporting bed being shown in section, on line 1-1 of Fig. 2; Fig. 2 is a plan view of the mechanism shown in Fig. 1, the saw and its 70 shaft being shown by dot and dash lines; Fig. 3 is a sectional view on line 3-3 of Fig. 2; Fig. 4 is a side view of a portion of the ring illustrating the slot formed therein; Fig. 5 is a side view of the ring portion 75 shown in Fig. 4; Fig. 6 is a face view of a ring casting which is slightly elliptical; Fig. 7 diagrammatically illustrates the ring 80 holder and the ring casting after the initial slotting operation which occurs with the ring shown in the position indicated by full lines, the ring and the holder being shown in an alternative position by dot and dash lines in which the ends of the ring at the slot initially formed therein are pressed inwardly; Fig. 8 is an enlarged view of a part 85 of the ring at the slot therein as the same appears in Fig. 7, this figure also diagrammatically indicating the use of the saw in trimming off the inwardly depressed ends of 90 the ring to bring the end faces of these ring ends into parallelism while they are inwardly depressed; Fig. 9 shows, by full lines, the 95 shape of the ring after it is released from the holder and in which the opposed end faces of the ring converge toward the interior of the ring instead of diverging, this figure also showing the shape of the ring when contracted to bring its end faces into parallelism and full engagement; Fig. 10 shows 100 a portion of the ring at the slot therein, the full lines indicating the full engagement of the ring ends which engagement is indicated by dot and dash lines in Fig. 9, the dot and dash lines in Fig. 10 indicating the relative 105 positions of the ring ends shown by full lines in Fig. 9; Fig. 11 diagrammatically illustrates, by dot and dash lines, the presence of a V-shaped gap that would intervene between the ends of the ring after the initial slotting operation and without the subsequent trimming operation, the full lines in 110

this figure illustrating the shape of the ring, when uncontracted, which shape is also illustrated by full lines in Fig. 7; and Fig. 12 illustrates, by full lines, the V-shaped gap 5 shown by the dot and dash lines of Fig. 11, the dot and dash lines in Fig. 12 indicating the relative positions of the unfinished ring ends shown by the full lines in Figs. 7, 8 and 11.

10 The ring casting 1, shown in Fig. 6, is slightly elliptical, the horizontal diameter of the ring, as shown in this figure, being the major diameter thereof, the notch 2 in the ring being located in a flatter side of the 15 ring on the minor diameter thereof and serving to indicate the location of the slot that is to be formed. The ring casting is placed in a holder, this holder being inclusive of a plate 3 which has holding formations 4 thereon receivable within the interior of the ring and holding formations 5 thereon upon the exterior of the ring. These holding formations are desirably in the form of rollers which are carried by pins 6 that project 20 from the plate 3. The holding formations 4 are in snug engagement with the ring at the ends of the major diameter of the interior of the ring to prevent material reduction in the major diameter of the ring during the manipulation of the ring. The holding formations 5 are on opposite sides of the gap 7 formed in the plate 3 for the reception of a saw which is desirably inclusive of two circular blades 8 fixed upon the same rotating shaft 9.

40 In the first step of the method, the saw serves to remove a section of the ring casting with the result that a wide slot is formed between the ends of the ring, the opposing faces of this slot being initially parallel, as shown in full lines in Figs. 7, 8 and 11 and by dot and dash lines in Fig. 12. If the operation were to stop with the initial formation of the slot, a V-shaped gap 10, shown 45 by full lines in Fig. 12 and by dot and dash lines in Fig. 11, would be formed between the ends of the ring when the ring is contracted while in service. To avoid this objectionable V-shaped gap, the opposed ends 50 of the ring are trimmed by the saw 8 after the ring ends are pressed inwardly to the positions illustrated by dot and dash lines in Figs. 7 and 8. When the ring ends are thus pressed inwardly, the opposing faces thereof diverge toward the interior of the ring, the saw 8 being again employed to trim the ends of the ring and bring their opposing faces into parallelism while the ring ends are still inwardly depressed. 55 When the ring is released, the opposed faces of the trimmed ends of the ring will converge toward the interior of the ring, as shown by full lines in Fig. 9 and dot and dash lines in Fig. 10, to such an extent that 60 these ring ends will be in parallelism and in

full or nearly full engagement when the ring is contracted while in use, as indicated by dot and dash lines in Fig. 9 and full lines in Fig. 10. The means for pressing the ring ends inwardly, at the slot, preferably resides in a block 11 having teeth 12 which engage the outward side of the ring opposite the slot therein. By moving the block 11 toward the slot to the position diagrammatically indicated by dot and dash lines in Fig. 7, the ends of the ring at the slot are pressed inwardly to the desired extent.

65 In the preferred embodiment of the invention, the shaft 9 which drives the saw 8 desirably has a normally fixed axis of rotation in which event the plate 3 is provided with a rib 13 which enters a groove 14 formed in the bed 15 of the machine. In the sawing operation, the plate 3 is moved back and forth with its rib 13 in the groove 14 so as to enable the saw to form the slot in the desired direction which is shown in Figs. 4 and 5, the slot being angular to the plane of the ring so that when the ring is contracted the end faces of the ring will be 70 in lapping relation. The block 11 is disposed between the wings 16 formed upon the opposite upright sides of the plate 3. The block 11 is formed with upright slots 17 therethrough, bolts 18 having their stems 75 passing through these slots, the nuts and heads upon these bolts receiving the plate 3 and the block 11 therebetween to hold said block between the wings 16 of the plate. The bottom face of the block 11 is inclined 80 and engages the inclined face of the wedge block 19. A shaft 20 is in threaded engagement with the wings 16 of the plate 3. The shaft is provided with a head 21 by which it may be turned and as the shaft is turned, it is moved longitudinally of its axis by means of its threaded engagement with said wings. Nuts 22, 23 upon the shaft 20 determine the extent to which this shaft may be moved 85 longitudinally of its axis, said nuts engaging the wings 16 respectively adjacent thereto when the limit of motion has been reached. The wedge block 19 accompanies the shaft 20 in its longitudinal movement. When the slot is being initially formed, the shaft is 90 drawn to the right to move the wedge block to the right so as to position the block 11 to hold the ring casting for the initial slotting operation. When the slot has been initially formed, the shaft is moved to its extreme left hand position in order that the wedge block 19 may raise the block 11 to bend the ends of the ring, at the slot initially formed in the ring, inwardly in preparation 95 for the next operation of the saw upon the ring, as hitherto set forth. In the use of the machine, the plate 3 and the parts moving therewith are moved forwardly and backwardly for the initial slotting operation and are again moved forwardly and 100

105 In the preferred embodiment of the invention, the shaft 9 which drives the saw 8 desirably has a normally fixed axis of rotation in which event the plate 3 is provided with a rib 13 which enters a groove 14 formed in the bed 15 of the machine. In the sawing operation, the plate 3 is moved back and forth with its rib 13 in the groove 14 so as to enable the saw to form the slot in the desired direction which is shown in Figs. 4 and 5, the slot being angular to the plane of the ring so that when the ring is contracted the end faces of the ring will be 110 in lapping relation. The block 11 is disposed between the wings 16 formed upon the opposite upright sides of the plate 3. The block 11 is formed with upright slots 17 therethrough, bolts 18 having their stems 115 passing through these slots, the nuts and heads upon these bolts receiving the plate 3 and the block 11 therebetween to hold said block between the wings 16 of the plate. The bottom face of the block 11 is inclined 120 and engages the inclined face of the wedge block 19. A shaft 20 is in threaded engagement with the wings 16 of the plate 3. The shaft is provided with a head 21 by which it may be turned and as the shaft is turned, it is moved longitudinally of its axis by means of its threaded engagement with said wings. Nuts 22, 23 upon the shaft 20 determine the extent to which this shaft may be moved 125 longitudinally of its axis, said nuts engaging the wings 16 respectively adjacent thereto when the limit of motion has been reached. The wedge block 19 accompanies the shaft 20 in its longitudinal movement. When the slot is being initially formed, the shaft is drawn to the right to move the wedge block to the right so as to position the block 11 to hold the ring casting for the initial slotting operation. When the slot has been initially formed, the shaft is moved to its extreme left hand position in order that the wedge block 19 may raise the block 11 to bend the ends of the ring, at the slot initially formed in the ring, inwardly in preparation for the next operation of the saw upon the ring, as hitherto set forth. In the use of the machine, the plate 3 and the parts moving therewith are moved forwardly and backwardly for the initial slotting operation and are again moved forwardly and 130

backwardly for the finishing slot forming operation after the ring ends at the initially formed slot are bent inwardly. The stem 24 of a bolt passes upwardly through a slot 25 formed in the bed 15 along the groove 14. The head 26 of this bolt underlies the bed 15 and the nut 27 overlies the base extension 28 of the plate 3.

Having thus described my invention, I 10 claim:

1. Mechanism for slotting piston ring castings which are slightly elliptical including a holder for holding the ring; a saw, said holder and saw being relatively adjustable to enable the saw to form a slot having substantially parallel opposite faces through a flatter side of the ring; and means for pressing the ring inwardly at the slot to cause the opposed faces of the ring ends to 20 diverge toward the interior of the ring, the saw being again operative to shape the ring at the slot while the ring ends are thus positioned to bring the opposed faces of the ring ends substantially into parallelism.
2. Mechanism for slotting piston ring castings which are slightly elliptical including a holder for holding the ring; a saw, said holder and saw being relatively adjustable to enable the saw to form a slot having substantially parallel opposite faces through a flatter side of the ring; and means for pressing inwardly both of the ring ends at the slot to cause the opposed faces of the ring ends to diverge toward the interior of the ring, the saw being again operative to shape both ends of the ring at the slot while the ring ends are thus positioned to bring the opposed faces of the ring ends substantially into parallelism.
3. Mechanism for slotting piston ring castings which are slightly elliptical including a holder for holding the ring and including portions engaging the ring at the ends of its major diameter to prevent material reduction in this diameter of the ring; a saw, said holder and saw being relatively adjustable to enable the saw to form a slot having substantially parallel opposite faces through a flatter side of the ring; and means for 45 pressing the ring inwardly at the slot to cause the opposed faces of the ring ends to diverge toward the interior of the ring, the saw being again operative to shape the ring at the slot while the ring ends are thus positioned to bring the opposed faces of the ring ends substantially into parallelism.
4. Mechanism for slotting piston ring castings which are slightly elliptical including a holder for holding the ring and including portions engaging the ring at the ends of its major diameter to prevent material reduction in this diameter of the ring; a saw, said

holder and saw being relatively adjustable to enable the saw to form a slot having substantially parallel opposite faces through a flatter side of the ring; and means for pressing inwardly both of the ring ends at the slot to cause the opposed faces of the ring ends to diverge toward the interior of the ring, the saw being again operative to 65 shape both ends of the ring at the slot while the ring ends are thus positioned to bring the opposed faces of the ring ends substantially into parallelism.

5. Mechanism for slotting piston ring castings which are slightly elliptical including a holder for holding the ring; a saw, said holder and saw being relatively adjustable to enable the saw to form a slot having substantially parallel opposite faces through a flatter side of the ring, said ring holder including two ring engaging formations engaging the interior of the ring at the ends of its major diameter and a third ring engaging formation engaging the exterior of the ring adjacent the slot formed therein by the saw; and means for pressing the ring against the latter ring engaging formation to cause the end part of the ring engaging this formation to be pressed inwardly at the slot to cause the opposed faces of the ring ends to diverge toward the interior of the ring, the saw being again operative to shape the ring at the slot while the ring ends are thus positioned to bring the opposed faces of the ring ends substantially into parallelism.

6. Mechanism for slotting piston ring castings which are slightly elliptical including a holder for holding the ring; a saw, said holder and saw being relatively adjustable to enable the saw to form a slot having substantially parallel opposite faces through a flatter side of the ring, said ring holder including two ring engaging formations engaging the interior of the ring at the ends of its major diameter and two additional ring engaging formations engaging the exterior of the ring adjacent and opposite the sides of the slot formed therein by the saw; and means for pressing the ring against said additional ring engaging formations to cause the end parts of the ring engaging these additional formations to be pressed inwardly at the slot to cause the opposed faces of the ring ends to diverge toward the interior of the ring, the saw being again operative to shape both ends of the ring at the slot while the ring ends are thus positioned to bring the opposed faces of the ring ends substantially into parallelism.

In witness whereof, I hereunto subscribe my name.

CHARLES N. TEETOR.
